ABSTRACT OF THE DISCLOSURE

A process for producing light hydrocarbons and jet fuel boiling range paraffinic hydrocarbons which comprises averaging a raffinate rich in paraffins with another paraffinic feedstock selected from the group consisting of propane or C_4 or C_{10} to C_{20} hydrocarbons or mixtures of the foregoing hydrocarbons, to obtain at least C_5 and C_{10+} hydrocarbons.

CROSS-REFERENCES

This application is a continuation-in-part of now abandoned applications Ser. Nos. 864,870 and 864,871 filed Oct. 8, 1969, and also of applications Ser. Nos. 3,303 and 3,306, filed Jan. 16, 1970. The disclosures of the four applications cited above are incorporated by reference into the present patent application.

BACKGROUND OF THE INVENTION

The present invention relates primarily to averaging or the reaction of hydrocarbons of different molecular weight together in the presence of a catalyst to obtain new hydrocarbons. The present invention particularly relates to averaging alkane hydrocarbons.

The term "averaging" is used in this specification to mean conversion of feed components or hydrocarbon molecules of different molecular weight to at least components of intermediate molecular weight relative to the respective average molecular weights of the feed components. The term "averaging" is used herein to include, however, conversion to components of molecular weight higher than the average molecular weight of the heavier feed to the averaging reaction. For example, in an averaging reaction between butane and hexane, the butane and hexane are converted to hydrocarbons such as pentane, heptane, and octane.

Averaging of alkanes is discussed further in my applications Ser. Nos. 864,870, now abandoned 864,871, now abandoned. The averaging processes disclosed in Ser. Nos. 864,870 and 864,871 are preferably carried out at a relatively low temperature, usually below about 850° F. According to the aforementioned patent applications, the averaging reaction is carried out using a catalytic mass having hydrocarbon dehydrogenation activity and olefin disproportionation activity or using a catalytic mass comprising a Group VIII component and a Group VI-B component.

The present invention is particularly concerned with upgrading raffinate obtained, for example, as a side-product after extracting aromatics from the effluent hydrocarbons from a catalytic reforming process. Usually, the raffinate boils in the range of about C_8 and C_9 hydrocarbons or about 220–350° F. The raffinate is not particularly attractive as a gasoline, as the highly paraffinic raffinate has a relatively low octane rating. Also, the raffinate is not particularly suitable as a jet fuel because of its relatively low boiling range. Therefore, it would be desirable to convert the raffinate to C_{10+} hydrocarbons boiling in the jet fuel range and also to lighter paraffinic hydrocarbons such as C_5 hydrocarbons which could be used to obtain relatively high octane gasoline.

2

SUMMARY OF THE INVENTION

In accordance with the present invention, a process is provided for producing light hydrocarbons and jet fuel boiling range paraffinic hydrocarbons which comprises averaging a raffinate rich in paraffins with another paraffinic feedstock selected from the group consisting of propane or C_4 or C_{10} to C_{20} hydrocarbons or mixtures of the foregoing hydrocarbons, to obtain at least C_5 and C_{10+} hydrocarbons.

Preferably, the averaging is carried out by contacting the raffinate with a catalytic mass having catalytic activity for paraffin dehydrogenation as well as catalytic activity for olefin averaging.

A particularly preferred catalyst for the averaging of raffinate with other hydrocarbons fed to the averaging zone in the present invention comprises platinum on alumina and a Group VI-B metal on a refractory support. Preferred catalysts for use in the averaging zone in the process of the present invention are disclosed in applications Ser. Nos. 864,870, now abandoned, and 864,871, now U.S. Patent No. 3,593,432. It is preferred to carry out the averaging reaction at a temperature below about 850° F. and in the presence of no more than about 5 weight percent olefins.

One of the important advantages of the process of the present invention is that the process operates to convert raffinate to paraffinic C_{10+} hydrocarbons which are particularly valuable for use as jet fuel. The paraffinic hydrocarbons which result from the alkane averaging reactions in the process of the present invention have a much higher ASTM smoke point than aromatic hydrocarbons and therefore are particularly suitable for use as jet fuel. The term "jet fuel" or "jet fuel boiling range hydrocarbons" is used herein to mean hydrocarbons boiling in the range of about 300° F. to about 600° F. and more usually within the range of about 350° F. to 550° F.

The term " C_{10+} " is used in the present specification to mean hydrocarbons such as normal decanes or branched C_{10} hydrocarbons and higher hydrocarbons such as C_{11} , C_{12} , etc. As the present invention operates by way of alkane averaging reactions, preferably under conditions including a dehydrogenation-hydrogenation catalytic component, and preferably at relatively low temperatures to avoid a substantial amount of olefins, usually the C_{10+} hydrocarbons are predominantly paraffinic hydrocarbons with smaller amounts of naphthenes and aromatics, and a very small amount of olefins. The paraffin (alkane) content of the C_{10+} hydrocarbons produced in the process of the present invention usually is at least 75–90% by weight paraffins.

Various hydrocarbons can be averaged with the raffinate in the process of the present invention. Hydrocarbons such as propane or iso or normal butane or heavier hydrocarbons such as any of the hydrocarbons in the range C_{10} – C_{20} , or various mixtures of the above-mentioned hydrocarbons can advantageously be averaged with the raffinate in the process of the present invention. Light hydrocarbons such as propane and C_4 alkanes can be averaged with C_8 and C_9 rich raffinate to produce light hydrocarbons which can be used, in most instances after further processing, to form gasoline, and also minor amounts of jet fuel boiling range hydrocarbons. Thus, in using the C_3 or C_4 hydrocarbons for averaging with the raffinate, excess light hydrocarbons such as C_3 or C_4 can be upgraded in value by conversion to liquid hydrocarbons, including light gasoline boiling range hydrocarbons.

C_{10} to C_{20} hydrocarbons are particularly attractive for averaging with C_8 to C_9 raffinate because high yields of C_{10+} jet fuel are obtained when averaging the relatively heavy C_{10} to C_{20} hydrocarbons with the typical raffinate

rich in C_8 and C_9 paraffins. There is also a considerable amount of light gasoline boiling range hydrocarbons such as C_5 , C_6 , and C_7 hydrocarbons produced when averaging hydrocarbons in the range C_{10} – C_{20} with raffinate composed mostly of C_8 and C_9 paraffins.

The term "raffinate" is used in the present invention to mean any paraffin-rich hydrocarbon stream boiling mostly in the range of about C_6 to C_{10} and having been separated from a mixed hydrocarbon stream containing a substantial amount of aromatics. Preferably, the raffinate is rich in paraffins and contains at least 50 percent paraffins by weight and preferably 70–80 percent or more paraffins by weight. Particularly preferred raffinate for averaging in the process of the present invention are paraffinic rich raffinates obtained after extracting aromatics from the effluent from a catalytic reforming process. Catalytic reforming processes are those reforming processes wherein a hydrocarbon feedstock, usually a naphtha boiling range feedstock, is converted in the presence of a catalyst, usually a catalyst comprising platinum on alumina, to higher octane hydrocarbons, by means of dehydrogenation and cyclization reactions.

Preferably the averaging of the raffinate with other hydrocarbons is carried out at a temperature below 850° F., and more preferably, below 800° F., and in the presence of no more than about five weight percent olefins, by contacting the raffinate and other hydrocarbon feedstock with a catalytic mass having catalytic activity for dehydrogenation of paraffins as well as catalytic activity for olefin averaging. The catalytic mass can comprise a physical mixture of catalyst particles which are active for hydrocarbon dehydrogenation and catalyst particles which are active for olefin averaging. Preferably, the catalytic mass comprises a noble metal or a noble metal compound on a refractory support, in addition to an olefin averaging component. Thus, preferred catalyst masses include platinum on alumina particles mixed with tungsten oxide on silica particles.

It is preferred in the process of the present invention to operate the averaging reaction zone at a pressure above about 200 p.s.i.g., more preferably above about 400 p.s.i.g., and still more preferably above about 800 p.s.i.g. The elevated pressure has been found advantageous because it leads to higher conversion. The residence time of the reactant in the reaction zone increases with increasing pressure. Also, the equilibrium partial pressures of both olefin and H_2 formed from dehydrogenation of saturated hydrocarbons rise in direct proportion to the square root of the total pressure. Thus, relatively high pressures, of the order of 500–1500 p.s.i.g., are particularly preferred.

Although preferred operating conditions for the averaging reaction zone are as indicated above, broader operating conditions include a temperature between about 400 and 900° F., a pressure between 50 and 2000 p.s.i.g., and a liquid hourly space velocity between 0.5 and 5.0.

Although the present invention is primarily directed to the averaging of raffinates rich in paraffins with other particularly paraffinic feedstocks, the present invention can also be applied to the conversion of only raffinate feedstocks fed to the reaction zone in the process of the present invention. In this instance, the reaction is largely a disproportionation reaction as opposed to an averaging reaction. Thus, the C_8 hydrocarbons in the raffinate are disproportionated to form hydrocarbons such as a C_4 and a C_{12} hydrocarbon from two C_8 paraffins in the raffinate feed. There will, of course, be some averaging between the different molecular weight hydrocarbons in the raffinate feedstock itself, but the reaction will be primarily of a disproportionation character because of the relatively narrow hydrocarbon cut which typically makes up the raffinate feedstock.

EXAMPLES

(1) In this example, normal butane is averaged with a raffinate composed primarily of C_8 and C_9 paraffins.

The C_4 hydrocarbons can be obtained from various sources such as petroleum distillates or from excess butanes from hydrocracking or catalytic reforming or other refinery process operations. The raffinate used in this example was a raffinate left after solvent extraction of aromatics from a portion of the effluent from a catalytic reforming process.

The conditions used to carry out the averaging reactions included a temperature of about 800° F., a pressure of about 900 p.s.i.g., a feed rate of about 9 cubic centimeters per hour of 1 part by volume raffinate with 2 parts by volume normal butane, a liquid hourly space velocity of 1.0, and catalyst consisting of 2 parts by volume of a 0.5 weight percent platinum plus 0.5 weight percent lithium on alumina together with 7 parts by volume of 8.0% tungsten oxide (calculated as tungsten) on silica.

The feed composition and the product or result of the averaging reaction are shown in Table I below. As can be seen from Table I below, over 9% of incremental C_{10+} hydrocarbons was produced and the excess butanes were substantially upgraded to light hydrocarbons boiling in the C_5+ range which could be used in the production of gasoline. A portion of the feed to the averaging reaction was also converted to very light hydrocarbons such as C_2 and C_3 hydrocarbons. The propane can advantageously be used to produce liquified petroleum gas (LPG).

TABLE I

Component:	Feed, wt. percent	Product, wt. percent	Net change
C_1		0.53	+0.53

br- $C_{10}H_{22}$	1.79	6.88	+5.09
n- $C_{10}H_{22}$	0.27	0.23	-0.07
C_{11+}	0.98	5.08	+4.10

(2) In this example, a paraffinic-rich raffinate comprising mostly C_8 and C_9 hydrocarbons was averaged with a paraffin in the range C_{10} to C_{20} , specifically n-hexadecane (C_{16}). The reaction conditions were substantially the same as those used in the previous example, except that the temperature was 700° F. instead of 800° F. The feed to the reaction zone was 50 volume percent of C_8 – C_9 rich raffinate containing 82.1% paraffins, 12.3% naphthenes, and 57% alkyl benzenes, and 50 volume percent n-hexadecane.

With only one pass through the reactor, over 25 weight percent of the feed was converted to material boiling between the raffinate and n-hexadecane, specifically between about 350° F. and 550° F. Thus, a relatively high yield of jet fuel was obtained with only one pass operation. It is preferable to recycle most or all of the unconverted hydrocarbons boiling above 550° F. for averaging with raffinate to convert the unconverted 550° F.+ hydrocarbons to jet fuel and lighter hydrocarbons.

In the one pass operation, substantial amounts of gasoline boiling range hydrocarbons are produced in addition to the jet fuel boiling range hydrocarbons. The gasoline boiling range hydrocarbons can be withdrawn for use as gasoline blending stock or for further processing to increase the octane rating of the gasoline boiling range hydrocarbons, or the gasoline boiling range hydrocarbons can be recycled for further averaging.

A small amount of very light hydrocarbons are produced in any case, and these very light hydrocarbons can be used as LPG.

(3) In this example, only raffinate was fed to the averaging reaction zone. The raffinate was the same as the raffinate feed used in Example 2. Because only raffinate was fed to the reaction zone, the reactions were primarily disproportionation of hydrocarbon molecules such as C_8 or C_{10} molecules. However, some averaging reactions would occur between the C_8 and C_9 molecules present in the raffinate feed.

The conditions used to carry out the conversion of the raffinate included a temperature of about 800° F., a pressure of about 900 p.s.i.g., a liquid hourly space velocity of 1.0, and catalyst consisting of 2 parts by volume of a 0.5 weight percent platinum plus 0.5 weight percent lithium on alumina together with 7 parts by volume of 8.0% tungsten oxide (calculated as tungsten) on silica.

Table II below summarizes the results from the conversion of the raffinate as well as tabulating the feed composition of the raffinate. In one pass operation through the reactor, approximately one-tenth of the feed was converted to LPG, about one-fourth to light gasoline in the C_5 to C_7 range, and over one-sixth of the feed was converted to jet fuel range hydrocarbons.

In the table below, i stands for iso, n stands for normal, and br stands for branched chain. The relatively minor amounts of cyclic compounds present are included in Table II with the branched chain compounds, and cyclic compounds such as C_8 and C_9 naphthenes or aromatics fall in the branched chain C_8 and C_{10} weight percents, respectively.

Although various embodiments of the invention have been described, it is to be understood that they are meant to be illustrative only and not limiting. Certain features may be changed. It is apparent that the present invention has broad application to primarily averaging reactions wherein paraffinic-rich raffinate feedstocks are averaged with other hydrocarbons. Accordingly, the invention is

not to be construed as limited to the specific embodiments or examples discussed but only as defined in the appended claims.

I claim:

- 5 A process for producing light hydrocarbons and jet fuel boiling range paraffinic hydrocarbons which comprises reacting a raffinate containing paraffins boiling within the range C_6 to C_{10} with another paraffinic feedstock having paraffinic hydrocarbon molecules of different molecular weight than said raffinate and selected from the group consisting of propane, butane, or C_{10} to C_{20} paraffins in an averaging zone to obtain a product comprising hydrocarbons of intermediate molecular weight relative to said raffinate and said other paraffinic feedstock, wherein the reacting is carried out by contacting said raffinate and other paraffinic feedstock with a catalyst mass comprising a noble metal or noble metal compound on a refractory support and a Group VI-B metal compound on a refractory support, and wherein the reacting is carried out at a temperature below 800° F. and in the presence of no more than 5 weight percent olefins.

UNITED STATES PATENT OFFICE
CERTIFICATE OF CORRECTION

Patent No. 3,784,622

Dated January 8, 1974

Inventor(s) Thomas R. Hughes

It is certified that error appears in the above-identified patent and that said Letters Patent are hereby corrected as shown below:

Col. 2, line 21, "864,871, now U.S. Patent 3,593,432" should read -- 864,871, now abandoned -- .

Col. 2, line 46, "ar" should read --are--.

Col. 5, line 1, "averging" should read --averaging--.

Col. 5, line 3, "examplee" should read --example--.

Signed and sealed this 6th day of August 1974.
